(80) **Hague Agreement Data**

The ornamental design for an air purifier, as shown and described.

Int. Filing Date: **May 12, 2016**

DESCRIPTION

Int. Reg. No.: **DM/090882**

1. Air purifier
1.1 is a perspective view of an air purifier showing our new design in a normal position;

Int. Reg. Date: **May 12, 2016**

1.2 is a front elevation view thereof;

Int. Reg. Pub. Date: **Nov. 18, 2016**

1.3 is a rear elevation view thereof;

(30) **Foreign Application Priority Data**

1.4 is a left-side elevation view thereof;

Dec. 4, 2015 (KR) 30-2015-0061993

1.5 is a right-side elevation view thereof;

(51) **LOC (11) Cl.** **23-04**

1.6 is a top plan view thereof;

(52) **U.S. Cl.**

1.7 is a bottom plan view thereof;

USPC **D23/364**

1.8 is a perspective view of the air purifier in an operation position;

(58) **Field of Classification Search**

1.9 is a front elevation view thereof;

USPC D23/355, 356, 359, 364, 370, 386

1.10 is a rear elevation view thereof;

CPC A61L 9/00; A61L 9/02; A61L 9/03; A61L

1.11 is a right-side elevation view thereof;

9/034; A61L 9/04; A61L 9/12; A61L

1.12 is a top plan view thereof; and,

9/032; A61L 9/122; A61L 9/127; A61L

1.13 is a top plan view showing an example of a display part being activated, in the normal position.

9/22; B01D 46/00; B01D 46/0002; B01D

(Continued)

The broken line showing of portions of the air purifier is for the purpose of illustrating environment and forms no part of the claimed design.
